SEATBELT BUCKLE

Thomas E. Lohr, Warren, Mich., assignor to Jim Robbins
Seat Belt Co., Mount Clemens, Mich., a corporation
of Delaware

Filed May 8, 1969, Ser. No. 17,078

Term of patent 14 years

Int. Cl. D2—08

U.S. Cl. D2—408

FIG. 1

FIG. 2

FIG. 3

FIG. 4

FIG. 5

FIG. 6

FIG. 1 is a perspective view of a seatbelt buckle showing my new design;

FIG. 2 is a top plan view of the buckle shown in FIG. 1;

FIG. 3 is an end view substantially as seen from the right-hand side of FIG. 2;

FIG. 4 is a side elevational view substantially as seen from the bottom of FIG. 2;

FIG. 5 is an end elevational view substantially as seen from the left-hand side of FIG. 4; and

FIG. 6 is a bottom elevational view substantially as seen from the bottom of FIG. 4.

I claim:

The ornamental design for a seatbelt buckle, as shown.
